FASTENING DEVICE

Andrew M. Hexdall, Morris, Ill.

Application June 25, 1938, Serial No. 215,942

3 Claims. (Cl. 85—3)

The invention relates to devices for fastening or securing articles to apertured partitions having only one surface which is readily accessible. The term "partition" as used herein is intended to include all types of walls, ceilings or bulkheads. Necessity frequently arises for securing some article to a partition only one side of which is readily accessible, as, for example, securing a thermostat to a plaster wall in a house or a lighting fixture to a ceiling. In such cases it is desirable that some through-type of fastener be used, that is, one that extends entirely through the partition and is anchored on the opposite or inaccessible side.

5 The general object of the present invention is to provide a through fastening device of the character described which may not only be applied but also readily removed by manipulatory operations carried out on one side only of the partition to which it is secured.

10 A further object of the invention is to provide a fastening device of the type described which is very economical to make although rugged in construction and effective in operation.

15 Further objects and advantages of the invention will become apparent as the following description proceeds taken in connection with the accompanying drawing in which:

20 Figure 1 is a vertical sectional view of an apertured partition and a fastening device applied thereto embodying the present invention;

25 Figs. 2 and 3 are vertical sectional views similar to Fig. 1 illustrating various steps in applying the fastening device to the partition and removing it therefrom;

30 Fig. 4 is a transverse sectional view along the line 4—4 of Fig. 2;

35 Fig. 5 is a detail perspective view of an anchor plate included in the fastening device of Fig. 1.

40 The invention has been shown herein as embodied in a fastening device applied to a portion of a partition or wall 10 embodying a front layer of plaster 10^a and a back layer or reenforcing strip of wood 10^b. It will be understood, however, that the fastening device may be readily applied to partitions made of a large variety of different types of material such as wood, concrete, metal, plaster or combinations thereof. The article to be supported by the device may also

45 be any one of a large variety. In some instances it may be desirable to fashion the fastening device as part of the structure of the article supported, and in other instances to make it entirely separate.

50 In the particular embodiment of the invention herein illustrated the fastening device includes a flat base 11 which may, if desired, be provided with a border flange 12 to give it a box-like shape. Such additional parts of the base plate as the border flange may or may not

5 be included, depending upon the nature of the article to be supported. Any suitable means may be utilized for securing the supported article to the base 11. For the sake of economy in manufacture, the base plate 11 is preferably fashioned as a stamping from sheet metal.

An opening 13 is fashioned in the base 11 registering with an aperture 14 which is drilled or otherwise formed in the partition 10. In the present instance, the opening 13 is bordered by an integral laterally extending and slightly tapering flange 15, which projects into the partition aperture 14 and aids in securing the base 11 against displacement. In the event that the device is applied to a partition having at least a front layer made of relatively soft material, such as plaster or wood, projections may be fashioned on the flange 15 which bite into the partition material and hold the base 11 against rotation. These projections have been shown herein as formed by longitudinal flutes 16 on the flange 15. As a further means of holding the base 11 against skewing or rotation, a sharp pointed tongue 17 is struck out from the base plate to engage the partition. In the event that the device is applied to a partition having a hard front surface as, for example, when made of concrete the tongue 17 is, of course, omitted from the construction or else bent back into alignment with the base plate so that it will not engage the hard partition material which it is incapable of penetrating.

20 An elongated member resiliently yieldable in a longitudinal direction such as a helical tension spring 18 is secured to the base 11 adjacent the opening 13 and in a position to be inserted into the partition aperture 14. In the illustrative embodiment, the spring 18 has been shown as anchored at its outer end to a tongue 11^a struck out from the base plate 11. The resilient character of the spring permits it to be pivoted or swung laterally as, for example, from the position shown in Fig. 2 to that of Fig. 3. The spring 18 or similar yieldable member is made sufficiently small in diameter or cross-section that it may be moved laterally within the partition aperture 14 a substantial distance. In addition the untensioned length of the spring is made substantially less than the thickness of the partition to which it is to be applied.

25 An anchor member 19 is pivotally or movably secured to the free or inner end of the spring 18. This anchor member is, in general, dimensioned, first, to be inserted through the partition aperture 14 when swung into longitudinal alignment with the spring 18 (Fig. 2), and second, to overlie the edges of the partition aperture on the rear face of the partition when swung to a position transverse to the spring 18 (Fig. 1). The anchor plate 19 is also preferably fashioned as a stamping from sheet metal and may be of a channel or 30

half-round shape so as to fit snugly about the side of the helical spring 18 while being inserted through the partition aperture. The anchor plate 19 is pivotally or loosely connected at approximately its center 20 to the end of the spring 18. For this purpose the end of the spring is projected through an aperture in the anchor plate at its center and the end portion of the spring bent to prevent disengagement (Figs. 1 and 2).
10 In order to facilitate the application and removal of the fastening device, a lug 21 is struck out from the anchor plate 19 so as to present a shoulder on the interior thereof facing toward the pivot point 20 and longitudinally displaced therefrom. A tool (Fig. 3) may be provided for applying and removing the fastening device to the partition. The tool illustrated generally resembles a blunt pointed ice pick and comprises a long rod 22, insertable through the interior of the spring 18, and a handle 23. The blunt end of the rod 22 is dimensioned to engage the lug 21 on the anchor plate 19.

In applying the fastening device illustrated to the partition 10, the base plate 11 is first positioned on the front of the partition and the tongue 17 driven into the partition surface. At the same time, the spring 18 is inserted through the previously prepared partition aperture 14 and the fluted flange 15 is inserted into this aperture. During this insertion operation the anchor plate 19 is turned so that it is longitudinally aligned with the spring 18 and embraces the same. The tool rod 22 is then pushed through the center of the spring 18 and engaged with the lug 21 on the anchor plate 19. After having been engaged with this lug the tool is pushed in farther so that the spring 18 is extended and the anchor plate positioned approximately as shown in Fig. 2. The next step is to swing the tool upwardly to the position shown in Fig. 3, in which position the upper end of the anchor plate 19 is (by slightly withdrawing the tool) permitted to engage the inner face of the partition 10. Finally the tool is completely withdrawn and at the same time swung downwardly to its initial horizontal position during the withdrawal movement. As a result of such withdrawing operation, the anchor plate 19 fulcrums about its upper end, under the bias of the spring 18, and comes to rest in the position shown in Fig. 1. In this latter position the spring 18 holds the anchor plate 19 pressed tightly against the rear face of the partition so that the fastening device is held firmly against displacement.

If, at any time, it is desired to remove the fastening device, that may be done by carrying out the operations described above in substantially the reverse order. In general, the tool rod 22 is inserted through the spring 18 and pushed against the lower part of the anchor plate 19 so that the latter fulcrums about the upper end until the end of the tool contacts the lug 21. Inward pressure on the tool is then continued until the anchor plate swings into the position of Fig. 2. Then as the tool is moved axially outward, the spring 18 pulls the anchor plate longitudinally into the partition aperture 14. With the parts in that position the base plate 11 can be readily pulled from the front of the partition and the whole device removed intact. It will thus be seen that only a very simple tool is required in manipulating the fastening device described and that the various manipulatory operations are extremely simple to carry out. Furthermore, all

of the parts of the device always remain secured together so that none of them can be readily lost or mislaid and the device can be conveniently merchandised as a complete unit.

Although a particular embodiment of the invention has been shown and described in some detail for purposes of explanation of its various novel features, there is no intention to thereby limit the invention to such embodiment, but, on the other hand, the appended claims are intended to cover all modifications and alternative constructions within the spirit and scope of the invention.

I claim as my invention:

1. A device for securing articles to an apertured partition or the like only one side of which may be readily accessible comprising, in combination, a base member adapted to be positioned on the front of the partition adjacent the aperture therein, an elongated longitudinally yieldable resilient member secured to said base and adapted to be inserted into the partition aperture, an elongated anchor member pivotally secured at approximately the center thereof to the outer end of said yieldable member, and a projection on the inner face of said anchor member displaced from the point of its pivotal connection with said yieldable member and engageable by a tool inserted through the partition aperture to push said anchor member away from the inner face of the partition and pivotally into a position aligned with said yieldable member for the withdrawal of the anchor member through the partition aperture.

2. In a through-fastener device of the type described the combination with an apertured sheet metal base plate, of an integral longitudinally fluted flange on said base plate bordering the aperture therein and insertable into a registering aperture in a partition to frictionally engage the same, an anchor member adapted to engage the side of the partition opposite said base plate, and means carried by said base plate for yieldably and releasably holding said anchor member in position.

3. A device for securing articles to an apertured partition or the like only one side of which may be readily accessible comprising, in combination, a flat sheet metal base adapted to lie against the front face of the partition and having an opening therein registrable with the partition aperture, an elongated helical tension spring connected at one end to said base adjacent said base opening and insertable into the partition aperture, the untensioned length of said spring being substantially less than the thickness of the partition, an elongated channel-shaped sheet metal anchor plate pivotally connected to the free end of said spring at approximately the center of the inner side of said anchor plate, said anchor plate being movable from a position longitudinally aligned with said spring to a position transverse to the axis of the spring, and a projection on the inner face of said anchor plate displaced from its point of pivotal connection of said spring and engageable by a tool inserted from the base plate side of the device and through the center of said spring to push said anchor plate away from the inner face of said partition and pivotally into a position aligned with said spring for withdrawal of the anchor plate through the partition aperture.

ANDREW M. HEXDALL.
